United States Patent Office.

TIMOTHY J. SULLIVAN, OF ALBANY, NEW YORK.

Letters Patent No. 97,829, dated December 14, 1869.

IMPROVEMENT IN SAFES.

The Schedule referred to in these Letters Patent and making part of the same

To all whom it may concern:

Be it known that I, TIMOTHY J. SULLIVAN, of the city and county of Albany, State of New York, have invented certain new and useful Improvements in the Mode of Constructing Safes and Vaults; and I do hereby declare that the following is a specification of the same.

My invention relates to certain improvements in safes or vaults, hereinafter fully set forth.

In the drawings—

Figure 1 represents a perspective view of a section of a vault or safe, with a section of a vestibule and door embodying the several parts of my invention.

Figure 2 is a cross-section of a section of the same, showing the arrangements of the several parts and materials used, and the manner of uniting the same.

Figure 3 represents a longitudinal vertical view of the rabbet bars *g*.

A is the body of a safe or vault, and is constructed of iron and steel.

B is the vestibule leading to the body of a vault.

C is the door, hung by the usual hinges.

The body of the vault is constructed of plates *a*, of one-fourth inch boiler-iron, (usually,) and plates *c*, of steel, one-fourth inch, then plates of iron *a'* and plates of steel *c'*, then plates of iron *a''*, all of which are inter-riveted together by the rivets *r* and *r'*, as shown in fig. 2.

The plates of iron *a*, *a'*, and *a''* are bent at an angle to suit the form of the safe or vault to be constructed, and form continuous solid and unbroken corners, which corners must needs be cut or sniddered before a wedge could be applied, and which would effectually insure against the warping of the same when exposed to fire.

In the old manner of constructing safes, the iron plates *a*, *a'*, and *a''* butted against their contacting plates forming the corners, and were generally the weakest in such corners. But by this part of my invention the safe or vault is not only made stronger, but more secure against the assaults of burglars or fire.

b b are bars of iron, about one-half inch thick and three inches wide, inter-riveted with the body of the safe or vault, and are placed around in the corners of the same, inside, as shown in fig. 1, and form, with the plate *a''*, a sufficient depth of material (three-fourths of an inch) to hold any bolt *z* that might be screwed therein.

These bars *b* thus placed and secured dispense with the necessity of taking apart the several pieces when once secured together. For in the old manner of constructing safes and vaults with alternate plates of steel and iron, the several pieces were secured together, then drilled for the bolts *z*, when the said plates were then taken apart to tap with screw-thread the steel, and to harden the same, and finally, secured a second time,

which process of construction involved great labor and expense. This part of my invention saves all such labor and expense, and strengthens the safe.

d d are angle-irons placed around on the inside of the safe or vault, and over the bars *b b*, fig. 1, and shown by dotted lines in fig. 2; and instead of butting one angle-iron against the other in the corners, as has always been done, I form or turn the said angle-irons in a solid corner, *d'*, and in an angle that will be suited to the form of safe or vault being constructed.

This solid corner *d'* of the said angle-iron is made by turning and welding the same, and being thus made of a continuous solid piece, the safe or vault will be greatly strengthened. These solid corner angle-irons are secured to their places over the bars *b b* by the screw-bolts *z z*, which screw into the bars *b* and plates *a''*.

f is a heavy plate of boiler-iron, one-half of an inch or more in thickness, inter-riveted to the inside surface of the plates forming the vestibule *B*, which vestibule is constructed, as usual, of alternate plates of iron and steel, like the body of the vault. By the employment of the said heavy plate *f*, the vestibule is not only strengthened at what was always the weakest part, but the labor and expense attending the taking apart and securing together a second time the several plates, and the annealing and hardening the steel, is saved; and also a sufficient depth of material is found in the said plate *f* to hold any screw-bolts or rivets, which, in the old mode of construction, tended more to weaken the steel than strengthen it.

To further strengthen the vestibule *B*, at its junction with the body of the vault or safe *A*, I continue the said heavy plate *f* back and over the angle-iron *d'*, and secure one to the other by screw-bolts *z'*. By this part of my invention any and all strain or force that might be brought on the vestibule, to break the same away from the body of the safe or vault, would be more strongly resisted by reason of its connection with the body of the vault at the said angle-iron *d'* through the plate *f*.

g g are rabbet bars made of bars of iron about one-half inch thick and from three to six inches wide, which bars are riveted to the plate *f*, on the inside of the vestibule. The said rabbet bars *g* are formed with solid corners, as shown in fig. 3, and outline the inner surface of all the sides, top, and bottom, at the entrances. The solid corners of the said rabbet bars are placed at the corners, above and below, and the terminations of the limbs of their angles but against the ends of their adjacent bars. The said rabbet bars *g* are not only to receive the door-lock bolts, but also are to strengthen the vestibule in the jointures of the several sides, top, and bottom.

e e are lock-bolt holes, and are continued from

through the rabbet bars *g*, fig. 1, through the heavy plate *f*, as shown by dotted lines in fig. 2. By this part of my invention, any force that might be brought to strain on the door or door-frame, would, by reason of the lock-bolts entering both the rabbet bars *g* and the heavy plate *f*, be exerted on not only the said plate *f*, but on the angle-iron *d* of the vault, or on the bolts *z* holding the same, and on the bolts or rivets securing the exterior plates in a line of direction perpendicular to the said bolts or rivets.

To the door *C*, constructed of alternate plates of iron and steel inter-riveted together, I secure, by inter-riveting, the heavy plate *h*. The said plate is of boiler-iron, and one-half inch or more in thickness, and is to receive the usual studs, which secure the lock-frame to the door, and, being of sufficient thickness, does not necessitate the drilling of the iron and steel plates, to receive the usual studs of the lock-frame, which are screwed in their places and riveted. By this part of my invention the door is not only made stronger, but the labor of taking apart and securing together a second time the several plates of the door, that the steel might be properly drilled, tapped, and hardened, is dispensed with.

Having described my invention,

What I claim, and desire to secure by Letters Patent, is—

1. In safes or vaults, the exterior plates of which consist of alternate layers of iron and steel, constructed

and inter-riveted together as described, the bars or strips *b* placed around the corners or joints of the several sides inter-riveted to the body of the safe, and having the plate or plates *b'* secured to the said strips *b*, as set forth.

2. The heavy plate *f*, in combination with the plates *a c a' c'*, forming the vestibule, substantially as and for the purpose set forth.

3. In vaults or safes, strengthening the jointure of the vestibule with the body of the vault by securing the plate *f* to the angle-iron *d*, substantially as and for the purpose set forth.

4. The lock-bolt holes *e e*, when made into the rabbet bars *g* and continued through the plate *f*, the line of direction of the said bolt-holes being perpendicular to the plate *f*, substantially as and for the purpose set forth.

5. In safe or vault-doors, the exterior plates of which consist of alternate layers of iron and steel constructed and riveted together, the plate *h* riveted to the back of said door, as set forth.

6. The body *A* of a safe, when provided with the vestibule *B* and door *C*, all the parts being constructed and arranged as set forth.

T. J. SULLIVAN.
